DRAFT RIGGING

Donald S. Barrows, Rochester, N. Y., assignor to
 The Symington Company, Rochester, N. Y., a
 corporation of Maryland

Application November 6, 1931, Serial No. 573,501

10 Claims. (Cl. 213—22)

This invention relates to railway draft rigging, and, more particularly, to such in which draft sills movably mounted with respect to a railway vehicle underframe are employed.

5 The principal object of my invention, generally considered, is the provision of a railway vehicle underframe with floating sills, or sills longitudinally movable with respect thereto, said sills carrying mechanism at either end adapted to cushion 10 relative movement of the drawbars with respect to said sills, and intermediate mechanism adapted to cushion relative movement of the sills with respect to the underframe and body of the railway vehicle.

15 Another object of my invention is the provision of a railway vehicle with sills longitudinally movable with respect to the underframe and body thereof, said sills carrying stop means adapted to engage other stop means carried by the underframe or car body to limit longitudinal sliding movement of said sills with respect to said body, mechanism being provided for not only cushioning relative movement of the couplers or drawbars with respect to said movable sills, but for 20 cushioning movement of said movable sills with respect to said underframe.

25 A further object of my invention is the provision of railway draft rigging involving end gears and a gear intermediate said end gears, said gears being carried by floating sills longitudinally movable with respect to the body of the railway vehicle, a yoke being provided for operatively connecting the intermediate gear to the car underframe for actuating said gear when the floating 30 sills move in one direction.

35 A still further object of my invention is the provision of a railway vehicle involving an underframe and draft sills slidable with respect to said underframe, said sills carrying mechanism at each end adapted for cushioning movement of the couplers with respect to said sills, and cushioning mechanism intermediate the ends of said sills, said last-mentioned mechanism being operatively connected to the underframe for cushioning 40 movement of the sills with respect to said underframe in both directions.

45 Other objects and advantages of the invention relating to the particular arrangement and construction of the various parts will become apparent as the description proceeds.

50 Referring to the drawings illustrating my invention, the scope whereof is defined by the appended claims:—

55 Figure 1 is a fragmentary vertical longitudinal sectional view of a railway vehicle underframe

and portions of the associated vehicle body illustrating one embodiment of my invention, the associated cushioning mechanism and some of the associated rigging being shown in side elevation.

5 Figure 2 is a fragmentary vertical longitudinal sectional view of a railway vehicle underframe, supplementary to the view shown in Figure 1, so as to illustrate that portion of the underframe immediately adjacent and rearward of the part shown in Figure 1.

10 Figure 3 is a fragmentary plan of the underframe and mechanism shown in Figure 1, with parts in horizontal section.

15 Figure 4 is a fragmentary plan of the underframe and mechanism shown in Figure 2, with parts thereof in horizontal section.

20 Figure 5 is a fragmentary transverse sectional view on the line 5—5 of Figure 1, looking in the direction of the arrows.

25 Figure 6 is a fragmentary transverse sectional view on the line 6—6 of Figure 1, looking in the direction of the arrows.

Figure 7 is a fragmentary transverse sectional view on the line 7—7 of Figure 2, looking in the direction of the arrows.

30 Figure 8 is a fragmentary transverse sectional view on the line 8—8 of Figure 2, looking in the direction of the arrows.

35 Figure 9 is a fragmentary vertical longitudinal sectional view corresponding to Figures 1 and 2, but showing an alternative or modified form of my invention.

Figure 10 is a fragmentary plan of the underframe and mechanism shown in Figure 9, with parts thereof in horizontal section.

40 Figure 11 is a fragmentary transverse sectional view on the line 11—11 of Figure 9, looking in the direction of the arrows.

45 Figures 12 and 13 are views corresponding, respectively, to Figures 9 and 10, but showing another alternative or modified form of my invention.

50 Figure 14 is a view corresponding to Figure 13, but showing another modification.

Figure 15 is a view corresponding to Figure 14, but showing still another modification.

55 Figure 16 is a view corresponding to Figure 15, but showing still another modification.

Figure 17 is a fragmentary plan, with parts shown in horizontal section, showing a detail which may be used alternatively in the forms of my invention shown in Figures 13, 14, 15 and 16.

60 Figures 18 and 19 are views corresponding, respectively, to Figures 1 and 2, but showing an additional embodiment of my invention.

Referring to the drawings in detail, like parts being designated by like reference characters, and first considering the embodiment of my invention illustrated in Figures 1 to 8, inclusive, 5 there is shown a portion of a railway vehicle or car involving relatively fixed longitudinal frame members 1 to which are connected the bolster transoms 2, the bolster top cover plate 3, and the bolster bottom cover plate 4. Between said cover 10 plates 3 and 4 is mounted a combined limiting stop and center filler casting 5. The end sill 7 desirably connects the frame members 1 at the ends and is, in turn, connected to the end sheathing 8 and has castings 9 connected thereto. 15

15 Mounted between the longitudinal members or fixed sills 1 are floating sills 10, said sills being supported in any desired manner so as to move longitudinally with respect to the underframe and fixed sills 1, and, therefore, preferably sliding 20 on the bottom bolster cover plate 4 and slidably supported by the castings 9 in a manner as shown most clearly in Figure 5. At each end of the vehicle the sills 10 are desirably connected by a combined striking casting and sill tie member 11 preferably provided with a removable coupler carrier block 12 so as to adapt the arrangement for use with a drawbar comprising a swivel butt coupler 13. The sills 10 are also desirably connected by a filler casting 14 which functions 25 as a stop, or movable backstop, for the associated yoke 15, as well as being adapted to engage the fixed stop 5 to limit relative movement of said sills 10 with respect to the underframe. The stop 14 desirably has extensions 16 straddling or lying 30 on either side of the stop 5 and functioning to maintain the sills centered with respect to the stop 5, as well as providing the desired riveting area for connection of the stop 14 to said sills. 35

40 The yoke 15 desirably embraces cushioning mechanism 17 which, in the present embodiment, takes the form of a friction draft gear comprising a housing or casing 18 receiving friction wedges 19 urged apart by curved plate springs 20. Carrier irons 21 and 22 desirably connect the sills 10 beneath the mechanism 17 and serve 45 for the support of the latter. A cover plate 23 is desirably provided for connecting the sills 10 above the mechanism 17, as shown most clearly in Figures 1 and 6. Corrugated friction or 50 wear members 6' are desirably attached to the sills 10 above the cover plate 23 in engagement with and/or below the channel-shaped longitudinal frame member 6.

55 The coupler 13 is desirably connected to the yoke 15 as by means of a horizontal key 24, the ends of which are received in slots 25 provided in the sills 10, associated cheek plates 26, and rearward extensions of the combined casting 11. 60 A front follower 27 is desirably disposed between the butt of the coupler 13 and the draft gear 17, and supported as by means of a second key 28. In this way, relative movement of the draw-bar or coupler 13 with respect to the 65 sills 10, on both draft and buff, at each end of the car is cushioned, and movement of the sills 10 with respect to the underframe and body of the vehicle or car is limited by the clearance provided between the stops 5 and 14. 70

70 For cushioning relative movement of the sills 10 with respect to the underframe, a supplemental draft gear or cushioning mechanism 29 is provided, it being only necessary to provide such a gear 29 between the gears 17 and adj- 75 cent one end only of the car, although I do not

wish to be limited to this as, if desired, such a gear may also be provided adjacent the other end of the car. In the present embodiment, the gear 29 is double-ended, or of a form described and claimed in my application Serial No. 362,832, filed May 13, 1929. In brief, such a gear comprises a housing or casing 30 receiving friction wedges 31 urged apart by curved plate springs 32 at each end thereof, the outer ends of said wedges being engaged by a front follower 33 and a rear follower 34. The gear and followers are preferably supported by carrier irons 35 and 36, the followers 33 and 34 and associated gear 29 being embraced by a yoke 37 connected to the stop and filler casting 5 in any suitable manner, as by means of a draft key 38 extending through slots 39 in the yoke and a corresponding slot 40 in an extension 41 of the casting 5. The sills 10 are desirably connected by a cover plate 37' extending over the double-ended gear 20 29 and associated followers 33 and 34. 15

In order to effect actuation of the double-ended gear 29 for cushioning relative movement of the sills 10 with respect to the rest of the underframe and body of the car, the housing 30 is preferably connected to the movable sills 10 for movement with said sills, as by means of a draft key 38' extending through a slot 39' in the housing 30, and through slots 40' in the yoke 37 and slots 41' in the cheek plates 42 and/or movable 30 sills 10. 25

In order to prevent the followers 33 and 34 from falling or floating around when the sills 10 move in one direction or the other with respect to the members 1 and vehicle body, plates 43 and 44 are desirably used to connect the sills 10 forwardly of the front follower 33, and normally disposed adjacent said follower, so that when the sills move rearwardly under the action of buffing forces, the plates 43 and 44 will follow the follower 33 to hold it assembled with the associated wedge blocks 31 and springs 32 without effecting a compression of the front end of the gear 29. For the same reason, plates 45 and 46 are employed for connecting the sills 10 rearwardly of the rear follower 34, so that the follower 34 will be prevented from falling when the sills 10 move forwardly under the action of draft forces. These plates 43, 44, 45 and 46, of course, perform the additional function of properly spacing the sills 10 and rigidifying the connection therebetween. 40

From the foregoing disclosure, it will be apparent that although only one end of the car underframe is illustrated, I propose to provide a draft gear 17 adjacent each end of the car and a double-ended gear 29 rearwardly of the bolster adjacent one end only of the car, although I do not wish to be limited to the employment of only one gear 29. It will, therefore, be seen that when draft forces are applied to the coupler 13, the movement of the coupler with respect to the sills 10 is cushioned by compression of the gear 17 against the follower 27 held in place by the key 28 through the draft action of the yoke 15 through its connection with the coupler 13 by the key 24. 50

If the pulling force applied to the coupler is sufficient to overcome the frictional resistance between the sills 10 and the bolster cover plates 4, as well as the frictional resistance between the supporting lugs 47 and the carrying castings 9, the sills 10 will move relatively to the filler castings 5, moving the housing 30 of the double-ended gear 29 by the connecting draft key 38 over the front wedges 31 and associated plate springs 32, 75

so that the front end of the gear is compressed against the front follower 33 and associated extension 41 of the filler casting 5 which functions as a front stop for the gear 29. The clearance 5 between the filler castings 5 and 14 at the other end of the car is sufficient to permit enough movement of the sills 10 with respect to the underframe and body of the vehicle so that a full compression of the front end of the gear 29 10 may be effected, provided sufficient force is applied to the coupler 13.

When the coupler 13 is subjected to the action of buffing forces, such forces are cushioned upon movement of said coupler with respect to the sills 15 10 by direct compressive action through the front follower 27 and housing 18 to slide said housing over the associated wedges 19 and curved plate springs 20 against the rear follower 23', the rear end of the yoke 15 and stop casting 14. If sufficient buffing force acts on the coupler to overcome the resistance to movement of the sills 10 with respect to the body of the vehicle, said sills will slide rearwardly and actuate the rear mechanism 20 of the double-ended gear 29 through the key 38 25 against the rear follower 34, which is held from rearward movement by the yoke 37 connected to the extension 41 of the filler casting 5 by the key 38. The clearance between the castings 14 and 5 is sufficient to permit full compression of the rear 30 mechanism of the double-ended gear 29 when sufficient buffing force is applied to the coupler 13.

Referring now to the embodiment of my invention illustrated in Figures 9, 10 and 11, a construction is there shown which is substantially 35 identical with that of the embodiment in Figures 1 to 8, inclusive, the difference being that a greater relative movement and cushioning capacity between the movable sills 10^a and longitudinal frame members 1^a and body of the vehicle is provided for by adding cushioning spring groups at each end of the double-ended or selective travel gear 29a. These added cushioning units provide a different resistance curve, as they are preferably designed to close solid before the 40 associated friction gear. At the same time, a greater clearance is necessarily provided between the filler casting 14^a connecting the movable sills 10^a and the bolster center filling casting 5^a connected to the bolster cover plates 3^a and 4^a.

50 In the present embodiment, the double-ended gear 29^a which cushions relative movement between the sills 10^a and the rest of the underframe of the vehicle is supported between the sills 10^a on carrier irons 21^a and 22^a, said sills 10^a being 55 connected over the housing 30^a of the gear by a cover plate 37^a. Each end of the housing 30^a receives friction elements 31^a urged apart by curved plate springs 32^a.

Disposed at either end of the gear 29^a is a 60 nest of cushioning springs, the front nest 33^a involving a front follower 48, a rear follower 49, and twin arranged double coil spring units 50 therebetween. The spring units 50 are desirably held in place by bosses 51 on the followers 48 and 49, and separated one from the other by a member 52 disposed therebetween, a carrier iron 53 desirably serving to support the cushioning unit. In the normal position, the front follower 48 abuts the buffing face of the extension 41^a 65 of the filler casting 5^a, and the rear follower 49 abuts the wedges or friction elements 31^a of the gear 29^a.

The spring cushioning unit 34^a disposed rearwardly of the gear 29^a preferably includes a front follower 54, a rear follower 55, twin arranged

double coil spring units 56 supported on bosses 57 on the followers and separated by a member 58. It will be seen that the members 58 and 52 of the gears 33^a and 34^a and the supporting and centering bosses on the followers are of such size 5 that they go solid under full compression of the springs, thereby avoiding overstressing the spring units. A carrier iron 59 is desirably provided for supporting the spring cushioning unit 34^a.

When the mechanism of the present embodiment is subjected to draft or buffing forces, the action is identical with that of the previous embodiment, except that a greater travel is provided of the sills 10^a with respect to the vehicle body on account of the extra cushioning springs at the 15 ends of the gear 29^a. As in the first embodiment, connecting plates 43^a and 44^a are desirably provided between the sills 10^a forwardly of the front follower 48 and connecting plates 45^a and 46^a rearwardly of the rear follower 55 to keep said 20 followers assembled with respect to the associated mechanism upon movement of the sills 10^a with respect to the longitudinal members 1^a and casting 5^a in one direction or the other. On account of the greater height of the cushioning 25 units 33^a and 34^a as compared with the gear 29^a, the flooring 60 of the vehicle may be cut away locally, as indicated at 61, to avoid interference with said units.

Referring now to the embodiment of my invention illustrated in Figures 12 and 13, a construction is there shown in which the double-ended or selective travel gear 29 of the first embodiment is replaced by a usual form of gear 29^b comprising a housing 30^b receiving friction elements 31^b and 35 actuating curved plate springs 32^b in one end only, said gear and its associated follower 34^b being supported on carry irons 35^b and 36^b and disposed between front and rear followers 33^b, which followers are mounted on actuating draft 40 keys 62 and 63, respectively. The key 62 has its ends extending through slots 64 in the associated yoke 37^b and slots 65 in the cheek plates 66 and/or movable sills 10^b. The key 63 supporting the rear follower 33^b likewise has its ends received in slots 67 formed in cheek plates 68 and/or the movable sills 10^b. The yoke 37^b surrounds the gear 29^b and is connected to the bolster center filler casting and stop member 5^b, as in the preceding embodiment, by a connecting 50 key 39^b, so that the front follower 33^b is normally held in engagement with the stop portion of the extension 41^b of the bolster center filler casting 5^b.

Upon relative movement of the sills 10^b with 55 respect to the filler casting 5^b and body of the vehicle under the action of draft forces, the key 63 is pulled forwardly, compressing the gear 29^b against the front follower 33^b and extension 41^b of the casting 5^b. Under the action of buffing 60 forces, the front follower 33^b is pushed rearwardly by the associated key 62, compressing the gear 29^b against the follower 34^b held stationary by the yoke 37^b. As in the preceding embodiments, there is, of course, sufficient clearance 65 provided for permitting the sills 10^b to move sufficiently to effect a full compression of the gear 29^b.

Referring now to the embodiment of my invention illustrated in Figure 14, a construction is there disclosed which is identical with that of the 70 embodiment of Figures 12 and 13, except that the cushioning movement allowed by the gear 29^c is amplified by a spring cushioning mechanism 34^c which may be identical with the mechanism 34^a of the embodiment of Figures 9, 10 and 11. In 75

order to provide for a full compression of the gears 29^c and 34^c in series, the clearance for movement of the sills 10^e with respect to the longitudinal members 1^e and filler casting 5^e will have to be correspondingly increased, and the slots in the cheek plates 66^c, 68^c and the yoke 37^c likewise increased in accordance with the increased travel provided.

Referring now to the embodiment of my invention illustrated in Figure 15, a construction is there disclosed which is identical with the embodiment illustrated in Figures 12 and 13, except that a double-ended or selective travel gear 29^d and front and rear followers 34^d are substituted for the single-ended or usual friction draft gear 29^b and its follower 34^b. As in Figures 12 and 13, the double-ended gear and its followers are disposed between key-supported front and rear followers 23^d and surrounded by a yoke 37^d connected to the extension 41^d of the bolster center filler casting 5^d. The action on both draft and buff is identical with that of Figures 12 and 13, except that the double-ended gear 29^d provides for a somewhat increased travel which has to be taken care of by a corresponding increase in the length of the slots receiving the supporting keys 38^d, 62^d and 63^d, as well as a corresponding increase in clearance for allowing sufficient movement of the sills 10^d to fully compress the gear 29^d under both draft and buffing movements.

Referring now to the embodiment of my invention illustrated in Figure 16, a construction is there disclosed which is identical with that of Figure 15, except that an increased movement of the movable sills 10^e is provided by employing a spring cushioning unit 34^e adjacent one end of the double-ended gear 29^e, said unit and gear being embraced by a yoke 37^e connected to the extension 41^e of the bolster center filler casting 5^e. Of course, the slots receiving the supporting and connecting keys 38^e, 62^e and 63^e will have to be increased to correspond with the increased travel, as well as the clearance for movement of the sills 10^e with respect to the longitudinal members 1^e.

It should be further noted, not only in connection with the present embodiment, but also in connection with the embodiments of Figures 12 to 15, inclusive, that I am providing for the insertion of the keys associated with the mechanism which cushions relative movement between the movable sills and the underframe and body of the car by corresponding slots 69 in the fixed longitudinal members or sills 1^e. The slots 67^e which receive the key 63^e, and the corresponding slots (67, etc.) of the previous embodiments referred to, are extended forwardly an amount corresponding with the rearward elongation of the slots 65^e, and the corresponding slots (65, etc.) of the previous embodiments, which also corresponds with movement for full compression of the cushioning mechanism embraced by the yoke. This is not necessary, as the rear follower 33^e may move with the sills 10^e, although desirable to facilitate insertion and removal of the key 63^e.

Referring now to the embodiment of my invention illustrated in Figure 17, a construction is there disclosed in which the movable sills 10^f receive therebetween cushioning mechanism 29^f embraced by a yoke 37^f, said yoke abutting a fixed connecting member or stop 33^f rather than a rear key-supported follower. The possibility of such a stop in place of a follower for actuating the gear 29^f on draft is suggested by the pos-

sibility of the follower being fixed with respect to the movable sills. It will be understood that the mechanism 29^f, conventionally shown, may be of any desired type, for example, such as shown in any one of Figures 13 to 16, inclusive.

5

Referring now to the embodiment of my invention illustrated in Figures 18 and 19, a construction is there disclosed in which the single-ended mechanism 17 of the first embodiment is replaced by a double-ended or selective travel gear 17^g connected to the movable sills 10^g by a key 28^g extending through a corresponding slot in the housing 18^g and with its ends received in rearwardly elongated slots 70 in the cheek plates 71 and/or movable sills 10^g of the vehicle. The associated coupler or drawbar 13^g is, as in the first embodiment, supported on a carrier block 12^g which is, in turn, received in a combined striking casting and sill tie member 11^g connected to the outer ends of the sills 10^g, said outer ends being supported, as in the first embodiment, by castings 9^g connected to the end sill 7^g.

15

The coupler 13^g is desirably connected to a yoke 15^g by means of a key 24^g, said yoke embracing the selective travel gear 17^g and its associated front and rear followers 27^g, and the rear end of said yoke normally abutting the stop casting 14^g spaced from the relatively fixed bolster center filler casting 5^g a distance sufficient to provide for a full compression of the supplemental mechanism actuated upon movement of the sills 10^g with respect to the underframe and body of the car. This supplemental mechanism, as will be understood, may take any desired form, for example, as designated by the reference characters 29, 29^a and associated mechanism 33^a and 34^a, 29^b, 29^c and its associated mechanism 34^c, 29^d, or 29^e and its associated mechanism 34^e.

30

The gear 17^g is desirably supported on carrier irons 21^g and 22^g, to the former of which is desirably applied a follower stop 72 supplementing stops 73 on the sills 10^g which serve to prevent the front follower 27^g falling or floating around upon forward movement of the coupler 13^g with respect thereto. Sufficient normal clearance is, of course, provided between the front follower 27^g and the end sills 7^g and supporting casting 9^g to allow for the desired relative movement therebetween which is of course, the amount the body gear, or that gear which cushions relative movement between the movable sills 10^g and the fixed portion of the underframe and body of the vehicle, is compressed under the action of draft forces, plus an arbitrary distance allowed for clearance under full forward movement. The normal clearance allowed between the horn of the coupler 13^g and the striking casting portion of the combined casting 11^g is that amount necessary to effect a full compression of the mechanism at both ends of the selective travel gear 17^g, plus an arbitrary clearance on full compression. Similar clearances are, of course, provided in connection with other embodiments of my invention.

45

When draft forces are applied to the coupler 13^g, the movement of said coupler with respect to the sills 10^g is cushioned by compression of the mechanism at the rear end only of the double-ended gear 17^g, as the housing 18^g is held by the connecting key 28^g and the friction elements 19^g pushed into the housing against the pressure of the springs 20^g by the yoke 15^g key-connected to the coupler 13^g.

50

If the force applied to the coupler is sufficient to overcome the frictional resistance between the sills 10^g and the bolster cover plates 4^g, as well as

75

the frictional resistance between the sills 10^g and the supporting castings 9^g, said sills 10^g will move relatively to the filler casting 5^g and effect compression of the gear rearwardly of the casting 5^g 5 which is used for cushioning movement of the sills 10^g with respect to the fixed portion of the underframe and body of the vehicle, in a manner as clearly described in connection with the embodiment of my invention illustrated in Figures 1 10 to 8, inclusive.

When the coupler is subjected to the action of buffing forces, such forces are cushioned upon movement of the coupler with respect to the sills 10^g by the mechanism at both ends of the selective travel gear 17^g, which gear is compressed through the front follower 27^g, causing the friction elements 19^g at both ends of the housing 18^g to slide therein and be compressed against the rear follower 27^g, rear end of the yoke 15^g, and 15 filler casting 14^g, the slots 70 in the cheek plates 71 being correspondingly elongated to permit rearward movement of the housing 18^g with respect to the sills 10^g.

If sufficient buffing force acts on the coupler to 20 overcome the resistance to movement of the sills 10^g with respect to the body of the vehicle, said sills will slide rearwardly and actuate the mechanism rearwardly of the filler casting 5^g which serves to cushion relative movement between the 25 sills 10^g and the fixed portion of the underframe and body of the vehicle in a manner as clearly described in connection with the embodiment of my invention illustrated in Figures 1 to 8, inclusive. The clearance between the castings 14^g 30 and 5^g is, of course, made sufficient to permit full compression of said mechanism in accordance with the type of mechanism employed, that is, whether double-ended mechanism, such as designated by the reference character 29 is employed 35 by itself, or in combination with spring cushioning units, or whether single-ended cushioning mechanism, as designated by the reference character 29^b, is employed by itself, or in combination with spring cushioning units. As will be understood, either of the mechanisms 17 and 17^g may 40 be employed with any of the body cushioning mechanism 29 to 29^f, inclusive, within the scope contemplated by my invention.

In view of the foregoing disclosure, it will be 45 seen that I have devised cushioning mechanism for railway vehicles involving sills longitudinally slidable with respect to the body and remainder of the underframe of a railway vehicle, with associated cushioning mechanism which not only 50 cushions movement of the couplers with respect to said movable sills, but which cushions movement of the movable sills with respect to the remainder of the railway vehicle, a stop or stop means on the underframe performing the double 55 function of a back stop for the mechanism at one end of the vehicle which cushions movement of the coupler with respect to the movable sills and a front stop for the mechanism which cushions movement of said sills with respect to the remainder of the railway vehicle.

Although preferred embodiments of my invention have been illustrated, it will be understood that changes may be made within the spirit and scope of my invention as defined by the appended 60 claims.

I claim:—

1. In railway draft rigging, sills longitudinally slidable with respect to a railway vehicle underframe, a drawbar, cushioning mechanism interposed between said sills rearwardly of said draw-

bar, connecting means between said sills rearwardly of said cushioning mechanism for limiting rearward movement of said mechanism with respect thereto, stop means on said underframe for limiting rearward movement of said sills and 5 which function as a rear limiting stop for said mechanism, said sill-connecting means having extensions straddling said stop means to maintain said sills centered with respect thereto, other cushioning mechanism interposed between said 10 stop means, functioning as a front stop, and means connected to said stop means, followers disposed at either end of said other cushioning mechanism, and means passing through said followers for connecting them to said sills for actuating 15 said other cushioning mechanism upon movement of said sills with respect to said underframe.

2. In railway draft rigging, in combination with a railway vehicle underframe, sills longitudinally slidable with respect to said underframe, a drawbar mounted between said sills, cushioning mechanism interposed between said sills rearwardly of said drawbar, connecting means between said sills rearwardly of said cushioning 20 mechanism for limiting rearward movement of said mechanism with respect thereto, means operatively connecting said mechanism to said sills and drawbar for actuation on draft, stop means on said underframe adapted to be engaged by 25 said connecting means for limiting rearward movement of said sills, whereby it functions as rear limiting stop means for said cushioning mechanism, said sill-connecting means having extensions straddling said stop means to maintain 30 said sills centered with respect thereto, other cushioning mechanism interposed between said stop means, functioning as front stop means, and means connected to said stop means, said cushioning mechanism comprising a housing receiving 35 friction elements at each end, said housing being slotted, and means extending through said slot for connecting said housing to said sills for the alternate actuation of the mechanism at one end or the other as the sills move in one 40 direction or the other with respect to the underframe.

3. In railway draft rigging, in combination with a railway vehicle underframe, sills supported from said underframe and longitudinally slidable 45 with respect thereto, a drawbar mounted between said sills, cushioning mechanism interposed between said sills rearwardly of said drawbar, said mechanism comprising a housing receiving cushioning means in each end, a key extending 50 through said housing and said sills for operatively connecting said mechanism to said sills, a yoke embracing said mechanism, means connecting said yoke and drawbar, means connecting said sills rearwardly of said yoke for limiting rearward movement of said mechanism with respect to said sills, a stop on the underframe adapted 55 to be engaged by said sill connecting means for limiting longitudinal sliding movement of the sills with respect to the vehicle and functioning 60 as rear limiting stop means for said cushioning mechanism, the connection between said key and sills permitting rearward movement from normal but preventing forward movement whereby the cushioning means at both ends of the housing is 65 compressed on buff while that at only one end is actuated on draft, said sill-connecting means having extensions straddling said stop means to maintain said sills centered with respect thereto, and other cushioning mechanism disposed rear- 70

75

wardly of the stop on the underframe and serving to cushion movement of the sills with respect to said underframe with the stop functioning as front stop means.

4. In railway draft rigging, in combination with a railway vehicle underframe, sills longitudinally slideable with respect to said underframe, means rigidly connecting said sills intermediate the ends, stop means on said underframe adapted to be engaged by said connecting means for limiting relative movement of said sills with respect thereto, cushioning mechanism interposed between said stop means and means connected to said stop means, said cushioning mechanism comprising a housing, friction elements received in each end of said housing, the intermediate portion of said housing being slotted, and means extending through said slot for connecting said housing to said sills for the alternate actuation of the mechanism at one end or the other as the sills move in one direction or the other with respect to the underframe.

5. In railway draft rigging, in combination with a railway vehicle underframe, sills longitudinally slideable with respect to said underframe, stop means on said underframe, cushioning mechanism interposed between said stop means and means connected to said stop means, said cushioning mechanism comprising a housing, friction elements received in each end of said housing, and means extending through a slot in said housing for connecting it to said sills for the alternate actuation of the mechanism at one end or the other as the sills move in one direction or the other with respect to the underframe.

6. In railway draft rigging, in combination with a railway vehicle underframe, sills longitudinally slideable with respect to said underframe, stop means on said underframe, cushioning mechanism with one end engaging said stop means, a yoke embracing said cushioning mechanism and connected to said stop means, said cushioning mechanism comprising a housing, friction elements received in each end of said housing, the intermediate portion of said housing having a slot therethrough, and means extending through said slot for connecting said housing to said sills for the alternate actuation of the mechanism at one end or the other as the sills move in one direction or the other with respect to the underframe.

7. In railway draft rigging, in combination with a railway vehicle underframe, sills longitudinally slideable with respect to said underframe, stop means on said underframe, a friction draft gear and coil spring means acting in series with respect to one another and interposed between said stop means and means connected to said stop means, said draft gear comprising a housing, a slot in said housing and means extending

through said slot for connecting it to said sills for actuation thereof as the sills move in one direction or the other with respect to the underframe.

8. In railway draft rigging, in combination with a railway vehicle underframe, sills supported from, and longitudinally slideable with respect to, said underframe, mechanism serving to cushion movement of the sills with respect to said underframe, a portion of said underframe forming a front stop for said mechanism, and means rigidly connecting said sills and straddling said stop for centering purposes.

9. In railway draft rigging, sills longitudinally movable with respect to a railway vehicle underframe, means connecting said sills and limiting movement thereof with respect to said underframe, mechanism for cushioning movement with said sills with respect to said underframe, an underframe member functioning as a limiting stop for movement of said sills and as front stop means for said cushioning mechanism, said sill-connecting means straddling said underframe member for centering purposes and having an intermediate portion adapted to abut said member at the limit of its travel with respect to said underframe, means connected to said underframe member and embracing said cushioning means, followers disposed at either end of said cushioning means, and means passing through said followers for connecting them to said sills.

10. In railway draft rigging, in combination with a railway vehicle underframe, a coupler, a plurality of cushioning units arranged in series, one in advance of another, a portion of said underframe forming abutment means disposed between a rearwardly disposed unit and the unit forwardly thereof, one of said units being disposed intermediate other units, means for transmitting draft forces from said coupler to said intermediate unit, stop means cooperating with said intermediate unit to permit compression thereof under draft, stop means cooperating with said rearwardly disposed unit to permit at least partial compression thereof under both buff and draft, and means for causing buffing forces, imparted by said coupler to the foremost of said cushioning units, to be transmitted through said intermediate unit to said rearwardly disposed unit, and draft forces, imparted by said coupler to said intermediate unit, to be transmitted to said rearwardly disposed unit, said means comprising laterally spaced elements slidably mounted with respect to said underframe for transmitting forces past said stop means to the rearwardly disposed unit, whereby a greater proportion of the cushioning capacity is utilized for the absorption of buffing forces than for the absorption of draft forces.

DONALD S. BARROWS. 60
